UNITED STATES PATENT OFFICE.

CHESTER C. HARBRIDGE, OF DETROIT, MICHIGAN, ASSIGNOR TO DETROIT DEMOUNTABLE RIM COMPANY, OF DETROIT, MICHIGAN, A CORPORATION OF MICHIGAN.

TOOL FOR DEMOUNTABLE RIMS.

1,127,236.

Specification of Letters Patent.

Patented Feb. 2, 1915.

Application filed July 24, 1914. Serial No. 852,781.

To all whom it may concern:

Be it known that I, CHESTER C. HARBRIDGE, a resident of Detroit, in the county of Wayne and State of Michigan, have invented certain new and useful Improvements in Tools for Demountable Rims, of which the following is a full, clear, and exact description.

The invention relates to tools for demountable rims and more particularly to wrenches for loosening and removing wedge-lugs whereby the rims are secured on the wheel-body.

It has heretofore been the practice in some instances to provide flange-and-groove connections between the nuts and the wedge-lugs so that the wedge-lug would be moved positively with the nut, when the nut was turned in one direction to force the wedge into engagement with the rim, and when turned in the opposite direction to withdraw the lug from the rim. These wedge-lugs have portions fitting between the felly band and the rim and frequently become jammed in place so that considerable force is necessary to dislodge them. In other instances, no flange-and-groove connections were employed between the nut and the wedge lug and in these difficulty has been experienced in withdrawing the wedge-lugs from the rim.

The invention is designed to provide an improved tool whereby the lugs may be positively forced outwardly as the nut is being turned off and toward the end of the bolt, in securing devices in which there is no flange-and-groove connection between the bolt and the lug; so that said flange-and-groove connections for withdrawing the wedges may be dispensed with. The invention attains this object by means of an attachment to the tool or wrench employed for turning the nut, which is adapted to engage the inner face of the lug and to withdraw the lug with the nut.

Another object of the invention is to provide a device which may be employed on the usual form of wrench used for nuts on demountable rims.

The invention consists in the several novel features hereinafter set forth and more particularly defined by claims at the conclusion hereof.

In the drawings: Figure 1 is a perspective of the improved tool, the lug withdrawing

yoke being shown in inoperative position. Fig. 2 is a section showing the lug in operative position. Fig. 3 is a side elevation showing the lug-withdrawing yoke in operative position and the wheel in section. Fig. 4 is a detail axial section of the wrench member with the lug withdrawing loop thereon. Fig. 5 is an inner face view of a wedge lug, upon which the pulling yoke may be used.

The demountable rim illustrated comprises a felly 10, felly-band 11 thereon, and a removable rim 12 carrying a pneumatic tire 14, all of which may be of usual construction, as well understood in the art. Bolts 15 are secured in the felly and one end of each bolt extends through an opening 16 in a wedge-lug 17. This wedge-lug is provided with an inwardly extending portion 18 adapted to fit between the rim 12 and felly band 11 to support one side of the rim, the other side being seated upon a flange 19 on the felly band. The wedge lug 17 is provided with an inwardly projecting bearing-portion 20 at the lower end thereof so that the side 21 of said lug between bearing 20 and portion 18 will be spaced away from the side of the felly or the usual bearing plate 22 through which the bolt 15 passes. Nuts 24 are screw-threaded to the ends of bolts 15 and engage the side 21 of the lug and secure it in operative position. If desired, a spherical nut may be provided with a spherical bearing-surface 25 fitting in a correspondingly shaped seat 26 in the lug.

The improved tool comprises a member 27 having a socket 28 therein which is formed to fit around and is adapted to receive the nut 24 and to engage it so that the nut may be turned in either direction thereby. A shoulder 29 is formed in member 27 which is adapted to abut against the outer face of the nut so that as the nut is withdrawn from the bolt, member 27, as it turns with the nut, will be forced outwardly by the nut, thus causing member 27 to be moved longitudinally relatively to the bolt 15 as the nut is withdrawn from the bolt. Member 27 is rigidly secured to the shaft 30^a of a bail or crank 30 and a handle 31 is swiveled to the outer end 32 of the crank. By pressing the handle 31 inwardly in turning the crank 30 when a nut is held in socket 28, the nut may be quickly rotated in either direction.

A yoke 33 is pivotally and slidably mount-

ed on the crank 30 adjacent member 27. This yoke comprises a pair of arms 34, each provided with a lug or hook 35 and a connecting portion 36 having an opening 37 therein for the shaft 30^a. The lug is slideable upon said shaft so that when the tool is being used to turn the nut on the bolt, it can be slipped back on the shaft and away from the wedge-lug 17. Opening 37 is of sufficient size to permit a limited pivotal movement transverse to the axis of the shaft to permit lugs 35 to be swung into and out of engagement with the inner face of the side 21 of the wedge-lug when the nut is being turned off the bolt. Bearing 20 is somewhat narrower than the side 21 of the lug so that the hook and lugs 36 can be swung past the bearing into engagement with the inner face of side 21 of the lug and under wedge-portion 18. When the yoke has thus been shifted into engagement with the lug, which can be done after the member 27 has been placed on nut 24, as indicated in Fig. 2 and the crank 30 is turned to remove the nut from the bolt, the inner end of member 27, which has a shoulder 39, will engage the connecting portion 36 of the yoke, and as the nut is turned off the bolt, it will engage shoulder 29 in socket 28 and force member 27 outwardly with the nut. Resultantly, member 27 will force the yoke outwardly longitudinally of the bolt and hooks 35 will withdraw the wedge-lug with the nut. When the wedge-lug has been withdrawn sufficiently to release the rim or remove it from the bolt, the yoke may be disengaged from the wedge-lug by swinging it transversely to the axis of the crank shafts. When turning the nut to force the wedge-lug into operative position, the yoke may be swung into inoperative position as shown in Fig. 1.

The invention thus exemplifies a simple tool for removing wedge-lugs with the nuts which secure them to a wheel and which dispenses with the necessity of groove and flange connections between the nut and the lugs. The means employed for withdrawing the lugs can be quickly rendered operative when the nut is to be turned inwardly on the bolt.

The invention is not to be understood as restricted to the details set forth, since these can be modified within the scope of the appended claims without departing from the spirit and scope of the invention.

Having thus described the invention, what I claim as new and desire to secure by Letters Patent, is:—

1. A rim tool comprising a member having a nut-socket therein, means for turning said member, and pulling means for a wedge-lug operated by said member.

2. A rim tool comprising a member having a nut socket therein, means for turning

said member, and pulling-means operated longitudinally of the axis of the nut to positively withdraw the lug with a nut in the socket.

3. A rim tool comprising a member having a nut socket therein, means for turning said member, and pulling means adapted to engage the inner face of a wedge-lug, said socket-member having a shoulder for engaging said pulling means to withdraw the lug with a nut in the socket.

4. In a rim tool, the combination of a member having a nut socket therein, turning means rigidly secured to said member, and a pulling yoke provided with means for engaging the inner face of the side of a wedge-lug said member being provided with means for shifting the yoke to withdraw said lug with a nut in the socket.

5. In a rim tool, the combination of a member having a nut socket therein, a crank rigidly secured to said member and a yoke provided with pulling means formed to extend around the sides and to engage the inner face of a wedge-lug and operated by said member to withdraw said lug with a nut in the socket.

6. In a rim tool, the combination of a member having a nut socket therein, a crank rigidly secured to said member and a yoke provided with means for engaging the inner face of the side of a wedge-lug, said member having a shoulder for engaging the yoke to withdraw the lug with a nut in the socket.

7. A rim tool comprising a member having a nut socket therein, means for turning said member, and pulling means operated by said member and formed to engage the inner face of a wedge-lug and withdraw the lug with a nut in the socket, said pulling-means being pivotally movable relatively to said member.

8. A rim tool comprising a member having a nut-socket therein, means for turning said member, and means operated by said member and adapted to engage the inner face of a wedge-lug to withdraw the lug with a nut in the socket, said withdrawing-means being slidably to and from said member.

9. A rim tool comprising a member having a nut-socket therein, means for turning said member, and means operated by said member and adapted to engage the inner face of a wedge-lug to withdraw the lug with a nut in the socket, said withdrawing-means being pivotally movable with respect to said member and slidable to and from said member.

10. In a rim tool, the combination of a member having a nut socket therein, a shaft having a crank thereon secured to said member, and a yoke connected to said shaft and having hooks for engaging the inner face of a side of a wedge-lug, said socket member

having means thereon for engaging the yoke to withdraw the lug when the nut is turned in one direction.

11. In a rim tool, the combination of a member having a nut socket therein, a crank shaft secured to said member, and a yoke 15 slidably connected to said shaft and having hooks for engaging the inner face of a side of a wedge-lug, said socket member having means thereon for engaging the yoke to withdraw the lug when the nut is turned in one direction.

12. In a rim tool, the combination of a

member having a nut socket therein, a crank shaft secured to said member, and a yoke 15 slidably and pivotally connected to said shaft and having hooks for engaging the inner face of a side of a wedge-lug, said socket-member having means thereon for engaging the yoke to withdraw the lug 20 when the nut is turned in one direction.
